POCKET CASE AND MEMORANDUM PAD

Douglas J. Broughton, Springfield, Mass., assignor to Buxton, Incorporated, Springfield, Mass., a corporation of Massachusetts

Application November 20, 1947, Serial No. 787,185

3 Claims. (Cl. 281—19)

1

This invention relates to pocket cases and more particularly to pocket cases of the type which are provided with a memorandum pad or the like.

Pocket cases of the type to which this invention relates customarily comprise rear and front walls connected together along one side edge, one or both walls being provided with auxiliary pockets. In some forms the rear and front walls are also connected together along their lower end edges forming a pocket open along the top and one side edge. This latter construction presents particular problems where it is desired to carry a memorandum pad, and the principal object of the present invention is to provide a construction for carrying a memorandum pad which is equally applicable to both forms of case.

In the accompanying drawings,

Fig. 1 is a front elevational view of a pocket case, of the form in which the front and rear walls are connected along one side and bottom edge, and embodying my invention, parts being broken away;

Fig. 2 is a fragmentary front elevational view showing the pad carrier withdrawn from the case;

Fig. 3 is a fragmentary rear elevational view similar to Fig. 2;

Fig. 4 is a rear elevational view showing the carrier swung into operative position on the outer face of the rear wall;

Fig. 5 is a section substantially on line 5—5 of Fig. 2; and

Fig. 6 is a bottom edge view of the carrier and memorandum pad, the pivot rod being shown in section.

Referring to the drawings, the front wall of the case is shown at 1 and the rear wall at 2, the front and rear walls being connected together along one side edge as at 3 and along their lower edges as by stitching 4. As shown the front wall is provided with additional pieces 5 and 6 forming auxiliary pockets on the outer and inner faces respectively of the front wall. Such auxiliary pockets are however optional and not essential to the present invention.

Secured to the inner face of the rear wall is an intermediate wall member 7 secured to the inner face of the rear wall along its upper edge by stitching 8 and along its lower edge by the stitching 4 to form a pocket 9 opening along the free side edge of the rear wall. The free edge of the rear wall is provided at top and bottom with extensions 10 and 11, which are folded inwardly and included in the stitching 3 and 4 respectively to form restrictions at the end of the mouth of

2

pocket 9. Preferably a liner 12 of paper or thin leather and having dimensions only slightly less than the dimensions of the pocket 9 is cemented over the inner face of the intermediate wall member 7 to substantially cover the extensions 10 and 11.

Slidable within the pocket is a carrier member generally indicated at 13. Carrier 13 comprises a rear wall member 14 provided along one side edge with an extension 15 which is folded around a hinge member 16 which may be formed of stiffly flexible wire. The member 14 is formed with members 17 extending from the side edge opposite that which carries the extension 15, the members 17 have a length substantially equal to the width of member 14 and are folded over the face of member 14 with their free ends positioned to abut the hinge member 16 as best shown in Fig. 6. As shown in dotted lines in Figs. 4 and 5 the extensions 17 are positioned along the upper and lower end portions of the member 14.

A cover 18 preferably formed of flexible transparent cellulosic or plastic material is provided along one edge with one or more flexible hinge strips 19 preferably of fabric. The free edges of the hinge strips, as best shown in Fig. 6, extend under the edge of the extension 15 and above the ends of the extensions 17. A single line of stitching 20 secures the edges of extension 15, hinge strips 19 and extensions 17 to the member 14, and completes the hinging of the carrier as a whole to the wire 16.

As best shown in Figs. 5 and 6, the extensions or loops 17 receive the cardboard back piece 21 to which a plurality of sheets 22 are secured by a fabric binding 23 to form a conventional memorandum pad. As is apparent the pad is protected by the cover 18 from damage as the carrier is withdrawn or inserted in pocket 9.

40 The ends of the hinge member 16 extend outwardly beyond the ends of the carrier and are shaped to form heads, as indicated in dotted lines at 25 in Fig. 2, which heads engage the restrictions 10 at the ends of the pocket 9 when the carrier is withdrawn from the pocket as in Fig. 2. The complete separation of the carrier from the case is thus normally prevented. The rear wall 2 of the case is cut away as at 26 thereby permitting the carrier to be swung around hinge member 16 to a position where it lies flatly against the rear wall 2 of the case as shown in Fig. 4.

If it is desired for any reason to completely detach the carrier 13 from the case the wire hinge member may be "sprung" sufficiently to disengage

one of the heads 25 from the adjacent restriction 10.

As will be apparent an intermediate wall such as 7 may be applied to the rear wall of any type of pocket case to form a housing pocket for the carrier and that the presence of the carrier does not interfere with the use or capacity of the other pockets or elements of the case to which it is added. The carrier may be withdrawn and swung to operative position without disturbing the contents of the other pockets of the case.

The extension 15 extends over the inner edge of the outer hinge strip 19 which in turn extends over the inner edge of the cover 18 while the inner side edges of the sheets 22 forming the memorandum pad lie beneath the cover 18. Thus no exposed edges are presented in the direction of movement of the carrier into the pocket, preventing any tendency of the parts of the carrier or the pad sheets to become "dog eared" as the carrier is inserted in the pocket.

What I claim is:

1. A pocket case including front and rear walls connected together along one side edge, an intermediate wall member connected to the rear wall member to form a pocket opening along the free side edge of the rear wall, means restricting the opening of said pocket at its extreme end portions, a carrier member slidably mounted in said pocket, said carrier having projections extending from its end edges adjacent the inner side edge of the carrier, said projections engaging said restrictions, when the carrier is withdrawn from the pocket to hinge the carrier to the case, the free edge of the rear wall being cut away between said restrictions to permit the carrier to be swung flatly against the outer surface of the rear wall.

2. A pocket case including front and rear walls connected together along one side edge, an intermediate wall member connected to the rear wall

40

member to form a pocket opening along the free side edge of the rear wall, means restricting the opening of said pocket at its extreme end portions, a carrier member slidably mounted in said pocket, a wire member connected to the inner side edge of the carrier, and projecting beyond the end edges of the carrier to engage the restrictions at the ends of the pocket when the carrier is withdrawn from the pocket, the free edge of the rear wall being cut away to permit the carrier, when withdrawn from the pocket, to be swung about said wire as a hinge to lie flatly against the outer surface of the rear wall.

3. A pocket case including front and rear walls connected together along one side edge, an intermediate wall member connected to the rear wall member to form a pocket opening along the free side edge of the rear wall, the rear wall having extensions at the end portions of said free side edge, said extensions being folded inwardly of the pocket and secured to the inner face of the intermediate wall to form restrictions at the ends of the pocket opening, a carrier member slidably mounted in said pocket, the inner side edge of the carrier having an extending portion, a hinge member about which said extending portion is folded onto the front face of the carrier and a cover member provided along one side edge with a hinge strip, said hinge strip extending beneath said folded portion, the ends of said hinge member projecting beyond the ends of the carrier to engage said restrictions at the ends of the pocket when the carrier is withdrawn from the pocket, the free edge of the rear wall being cut away to permit the withdrawn carrier to be swung into a flat position against the outer surface of the rear wall.
